UNITED STATES PATENT OFFICE.

FRED E. MATTHEWS, OF LEONIA, NEW JERSEY.

FLUID-PRESSURE APPARATUS.

1,384,477.

Specification of Letters Patent. Patented July 12, 1921.

Application filed April 3, 1913. Serial No. 226,505.

To all whom it may concern:

Be it known that I, FRED E. MATTHEWS, a citizen of the United States, residing at Leonia, in the county of Bergen and State of New Jersey, have invented certain new and useful Improvements in Fluid-Pressure Apparatus, of which the following is a specification.

My invention relates to fluid pressure apparatus and more particularly to that type in which automatic safety pressure relief valves may be used to prevent failure of a part or parts of such apparatus under excessive internal pressure. It is especially applicable to apparatus which contains inflammable, asphyxiating, or offensive fluids which may give rise to additional fire hazards, danger to life, bodily discomfort, or financial loss when such fluids are discharged to the atmosphere through known forms of pressure relief valves.

One of the objects of my invention is to reduce danger to life and property due to disruptive pressures within such fluid pressure apparatus. Another object of my invention is to reduce danger to life and property due to the means now employed for preventing such disruptive pressures. Other objects will be in part obvious and in part hereinafter pointed out.

I propose to accomplish the above objects among others through the more general application of improved safety devices to such apparatus made practicable through means for insuring safety without entailing prohibitive fluid loss during such time as such safety devices are inoperative under conditions of normal pressure.

In order that a clear perception of the présent invention may be had it may be said to consist in general of the employment, in combination with fluid pressure apparatus, of one or more pressure relief valves of such peculiar design as will permit them to function substantially as described under the influence of predetermined initial pressures, substantially unaffected by the pressure or pressures against which they discharge. Similar or different types of devices responsive to pressures materially lower than that of the system proper for discharging from the system are employed for the fluid which passes such pressure relief valve or valves, as well as means for

taking up the fluid between such pressure relief elements and the pressure discharging element for reducing to a practical minimum the amount of fluid ultimately discharged from the system.

While I do not limit the application of my invention to such system, the one most eminently fitted for the purpose of illustrating its application, because of both the intrinsic value of the fluid and the serious and obvious disadvantages incident to its liberation into the atmosphere, and the one which I therefore employ in the following description, is an ammonia refrigeration system. This is understood to typify fluid pressure systems in general, and ammonia, herein-after frequently referred to in the specification and claims as "refrigerant," to typify fluids in general.

In the case of refrigeration machines, the high intrinsic value of the working media not only makes the cost of a given quantity of fluid lost a much more important item than in the case of steam, for example, but in some cases, notably that of the refrigerant anhydrous ammonia, the working pressure is not only higher, but the ability of the medium to pass through very small openings due to its molecular construction, is greater under the same pressure, both of which elements further tend to greatly increase the expense resulting from valve discharge and leakage entailed by present safety valve protection. On account of this expense and other disadvantages incident to leakage of refrigerant through automatic pressure relief valves it has been proposed to replace them by devices employing carefully fabricated plates, designed to rupture and release the refrigerant at a predetermined pressure, but the facts that there is no way for determining at exactly what pressure such plates will fail except by the destruction of the plate, and that such plates, even when carefully standardized fail under test at widely different pressures, makes their use directly under the maximum safe pressure to be controlled, prohibitive, especially since uncertainty of failure between comparatively narrow predetermined pressure limits may result disastrously to the system they are employed to protect.

The exact breaking point of such plates, as indeed that of all mechanical parts, be-

comes of less importance, however, as the factor of safety increases, or in the case in question, as the working margin between the point of probable failure and that of danger increases.

If, for example, a plate made to withstand a working pressure of 300 pounds is likely not to break in practice until that pressure has been exceeded by 50%, or until a pressure of 450 pounds is reached, its use would be impracticable. On the other hand, the devising of means whereby the protection of the system depends upon the rupture of a plate expected to break at 10 pounds, for example, but which might break under the same 50% overload at 15 pounds, under the original factor of uncertainty of 50%, the breaking pressure will still be far below that required for the safe operation of the system. A safe working pressure of 300 pounds for example, would be thirty times the probable, and twenty times the above assumed possible, breaking pressure of such a plate, and, having a factor of safety of from twenty to thirty it might therefore be safely depended upon for protection.

While it is obvious from the foregoing that the breaking of a plate can not be safely relied upon under high pressure as a substitute for the opening of a valve, and a plate therefore can not logically replace a high pressure valve it may nevertheless, be employed with the utmost safety under low pressure, in series with high pressure valves to prevent, for the time being, the escape of low pressure gas.

With the usual forms of safety valves, however, this would be impracticable since the variable pressures accumulating between the plates and the high pressure relief valve would variably affect the pressure at which such valves would function. By the use of a special type of safety valve, however, which operates at the predetermined pressure for which it is set regardless of the pressure discharged against, an accumulating pressure sufficient to rupture the plate would have substantially no effect on the safety of the system.

For present purposes it is necessary to describe the gas pressure relief valve I employ only as a valve capable of passing gas in either direction at a predetermined pressure, the opening of the valve being substantially unaffected by a pressure on the discharge side of the valve. In other words such a valve will be opened by the excess pressure of the medium entering the valve, over the substantially constant external pressure of the atmosphere plus an adjustably constant pressure imposed by a spring or other pressure imposing device. It may be pointed out that it is necessary to carefully differentiate between this type of valve and the ordinary pressure relief or safety valve, the opening

of which depends not wholly on the pressure to be relieved but on the difference between that and the pressure discharged against. It is obvious that the maximum protection which such latter valves are capable of providing is available only when they discharge against atmospheric or some other substantially constant pressure for which they are adjusted, the degree of protection furnished, decreasing as the pressure discharged against increases above that point. In the ideal case only, in which they open under an increasing pressure less a substantially constant discharge pressure, do they function practically the same as the valves I employ, which latter operate equally well under other conditions, being substantially unaffected by either constant or variable discharge pressures. Such a valve, functioning at any predetermined pressure for which it is adjusted, unaffected by the pressure discharged against, provides for the relief of all abnormal pressures. At the same time a gas tight plate or diaphragm, rupturable by a sufficiently low pressure to insure absolute safety, may be employed to prevent, absolutely, any loss of refrigerant by either leakage or discharge through such valves until such time as a pressure sufficient to rupture the plate or diaphragm has accumulated. Such a pressure may readily be sufficiently high to permit the use of refrigerant conserving means such as is hereinafter described.

The importance as well as the scope of my invention can best be explained by the aid of the accompanying drawings forming a part of this specification, in which—

Figure 1 is a diagrammatic representation of a refrigeration system, and Fig. 2 is a section of one of the valves. Referring to these drawings 1 indicates a compressor of a compression refrigeration system, for imposing the high pressure necessary for the liquefaction of the refrigerant. The refrigerant vapor is liquefied in condenser 2 by the effect of cooling water (not indicated) and the pressure developed by pump 1. A receiver, or reservoir 3 is provided for the liquefied refrigerant, and an expansion valve 4 controls the flow of liquid refrigerant to a refrigerator coil as evaporator 5 in which the liquefied refrigerant evaporates under reduced pressure thereby extracting heat from, and accordingly refrigerating the surrounding objects or material. Represented at 6, 7, 8 and 9 are pressure relief valves of a special type forming the subject of an application for Letters Patent on "improvement in valves," filed June 1st, 1917, Serial Number 172,212. A device 11 is provided having a rupturable diaphragm or plate capable of either automatic or hand actuation for discharging gases accumulating therein, either directly to the atmosphere, as for ex-

ample through a stack 12, or indirectly, as for example through a diffuser 13 into a body of water contained in a tank 14 by which the gases may be absorbed and conserved, or into the sewer after being mixed with water in passing through a mixing device 15. A refrigerant conserving 16, hereinafter described, is also provided. As the refrigeration system becomes complicated by the addition of other pressure imposing means, condensers, refrigerators, etc., involving additional interconnecting pipes and stop valves, it is obvious that the use of other pressure relief valves may become necessary. Additional refrigerators 17 and 18, for example, would require the use of the additional safety valves 19 and 20.

Having thus briefly set forth the objects of my invention and the general means for their accomplishment, I will now proceed to give a general description of the mechanical construction of the special devices employed. In Fig. 2 is shown semi-diagrammatically an axially sectional view of one form of my improved safety valve such as has already been constructed and successfully operated under practical conditions in connection with refrigeration systems of small capacity. The valve comprises essentially a central body 21 provided with the fluid passages 22, 23, 24 and 25, recesses 26 and 27, and inlet and outlet pipes 28—29, connecting passages 22 and 24, the end of passage 22 connecting with recess 26 terminating in a valve seat 30. Diaphragms 31 and 32 are clamped between body portion 21 and recessed cover plates 33 and 34 and a compression member 35 is interposed between diaphragms 31 and 32 and may be attached to either diaphragm, but not to both diaphragms. This member passes through a passage 25 mechanically incapable of transmitting pressure from recess 26 to that part of recess 27 below diaphragm 31. A hand controlled adjustable stop 36 limits the movement of diaphragm 31 as well as distends that diaphragm to cause member 35 to transmit pressure to diaphragm 32. A valve 37 carried by diaphragm 32 coacts with valve seat 30, and a spring 38 bears against diaphragm 32 on the side opposite valve 37 and is adjustable as to pressure by stop 40. The function of spring 38 is to afford an adjustable, substantially constant, predetermined, pressure on diaphragm 32, at or near its center, for the purpose of causing valve 37 to press home on valve seat 30, thereby effectively closing passage 22 whenever the pressure exerted by the spring 38 is greater than that exerted in the opposite direction by the fluid pressure in recess 26. The valve is capable of passing fluid in either direction under substantially the same pressure. By constructing my valve as above described, it will be seen that pressure entering through either pipe 28 or 29 will tend to unseat valve 37, and, therefore, as distinguished from ordinary check valves, pressure at the outlet side of the valve will not tend to seat the valve, and in this way its operation is substantially unaffected by the pressure discharged against. 70

The refrigerant conserving 16 such as has already been constructed and operated under practical conditions consists of a pressure resistant container 41, surrounded by an outer container 42 and filled with a refrigerant absorbent or reactant compound 43. Since the outer container 42 is for the purpose of holding the cooling medium 44 such as water, when compound 43 is employed for taking up the refrigerant, it is obvious that when either the capacity of the conserving is large or the quantity of the refrigerant taken up is small, in both of which cases only a small amount of heat, compared to the superficial surface of the container, 75 will be generated by the union of the compound and the refrigerant, air cooling may be substituted for water cooling, and this outer container 42 dispensed with. Since heat is normally employed for driving the refrigerant out of the absorbent compound, it may be effectively introduced through a coil of pipe 41' within container 41, which pipe coil may also be used for the introduction of cooling water. The ammonia conserving may assume a large number of forms, in some of which when as in the case shown only comparatively small absorbent surface would otherwise be exposed to the refrigerant, such surface may be largely increased 90 and the action of uniting the absorbent or reactant with the refrigerant, may be largely enhanced by the employment of perforated pipes 45. 95

The device 11 is provided with an easily rupturable diaphragm for allowing the refrigerant to escape from the system through means 12, 13, 14 or 15 should abnormally high pressures occur in the pipe connecting it with valve 8 because of abnormally heavy 100 discharge through valve 8 or failure, as upon saturation of the refrigerant absorbent or reactant compound 43 in the refrigerant conserving 16, to take up the refrigerant discharged through valve 8. 105

In its simplest form this device 11 containing a plate or diaphragm of any suitable material rupturable at a predetermined pressure, consists essentially of only a flange union or its mechanical equivalent between 110 the two members of which the rupturing member or plate is secured. In such a device the rupturing member would be designed to break under the direct pressure of the refrigerant. In more elaborate and 115 more positively reacting devices, inevitable variations in the pressure under which such rupturing members fail is eliminated by the liberation, by hand or by a predetermined refrigerant pressure working through some 120 125 130

auxiliary agency, of a normally restrained superior diaphragm rupturing force, such for example as might be exerted by a stiff spring or by the same refrigerant pressure 5 acting on a sufficiently large area. The liberation of this superior force might obviously be controlled from a considerable distance by the employment of a pipe for conducting the refrigerant or other fluid pressure, 10 by electrical means, or by numerous other devices commonly employed for similar distance control purposes.

The relief valve device 10 represents a means including a pressure responsive device 47, a signaling device 47', and a signaling device actuating means 48, caused to operate by the pressure responsive device, for giving audible warning that the pressure within that part of the conduit between the 15 refrigerant conserving means 16 and the refrigerant liberating means 11, is approaching the rupturing pressure of the diaphragm of such refrigerant liberating means. A pressure gage 46 gives similar, 20 visible warning. A duplicate of such audible and visible warning devices connected to discharge line 50 may be employed if desired to indicate conditions of impending 25 operation of the safety valve 8.

30 Gages 51 and 52 and valves 53, 54, 55 and 56 are unessential in so far as the functioning of the automatic safety devices herein described are concerned. Their employment is provided for however in certain 35 codes of safety regulations, their functions being to facilitate manual discharge from the system in case of fire.

Having thus pointed out the mechanical means which I employ in my invention, and 40 indicated something of their construction, I will now proceed to describe their operation in a system employing anhydrous ammonia for the production of refrigeration by the compression process. Under conditions of 45 normal or "forward" operation the refrigerant vapor leaving the refrigerator under comparatively low pressure, is subjected to the action of the compressor for increasing its pressure, after which it is discharged 50 through a stop valve 57 (and sometimes a check valve 58) in the discharge line 50, condenser 2, where upon being cooled, it liquefies and flows by gravity through a stop valve 59 into the liquid receiver 3 from 55 which it flows, still under pressure, to expansion valves 4, 60 and 61 on various "evaporators" which may consist of "expansion coils" such as 5 or "shell" brine coolers such as 17 or 18 in which the refrigerant is evaporated by heat absorbed from 60 the air and cold brine respectively. From the evaporators the vaporized refrigerant again passes under low pressure to the compressor or other pressure imposing means.

65 From the foregoing it is apparent that

excess refrigerant is normally stored in liquid receiver 3, the zone of high pressure beginning with the pressure imposing means and ending at the expansion valves. Under certain conditions however it may become desirable to reverse the flow of the refrigerant from the receiver and condenser, which together with other minor elements constitute the "high" pressure side of the refrigeration system, and store it in the 70 "low" pressure side of the system comprising that part of the system between the expansion valves and the pressure imposing means. To effect this change from "forward" to "reverse" operation, discharge stop 75 valves 62 and 57, respectively, are closed and a valve 63 in by-pass 64 is opened in which case refrigerant will be drawn from the "high" side through pipes 50 and 64 and discharge into the "low" side through 80 pipes 65, 66 and 67. Under present practice, both of the by-pass pipes 65 and 64 are provided with the usual type of hand actuated stop valve of which only one, 85 63, is retained in my system, the other one 20 being already embodied in the special safety valve 7 installed in the remaining by-pass pipe 65, 66.

In either the "forward" or the "reverse" operation just described the following contingencies to be provided for may arise:

1. The water supply may fail on the condensers giving rise to abnormal pressure in the "high" side of the system. Such condition unless remedied may eventuate disastrously. To meet this and other contingencies I employ two automatic valves 6 and 7 through which the refrigerant on reaching a predetermined pressure, is automatically passed to the "low" side of the system. In 105 the event that pressure accumulates on both the "high" and "low" sides of the system, slightly in excess of that required to actuate valves 6 and 7, valve 8 will function to discharge the refrigerant into conduit 70 110 (which may hereinafter be referred to as a "normally fluid tight chamber") which conveys it to the refrigerant conserving means 16. In the event that this member is not able to maintain a comparatively low 115 pressure by disposing of the gas, finally, as a last resort, to the diaphragm safety device 11 which upon opening, discharges it from the system. With proper attention, facilitated by the signaling devices such contingency need never arise due to leakage through valve 8 and, in fact, since that valve is set to discharge at a pressure slightly higher than valves 6 and 7 and much higher than valves 19 and 20, discharge from the 120 system due to the opening of valve 8 can occur only in the remote event of the existence of dangerous pressures simultaneously in both "high" and "low" sides of the 125 system.

2. Abnormal pressure in the pressure imposing element 1 may also result from accidental closing, or failure to open discharge valve 57 in which event the refrigerant discharge, not being able to pass valve 57, traverses pipe 65 to a cross 68 where three paths are provided. It can either pass through valve 6 to pipe 50 in the high pressure side of the system, through valve 7 to pipe 67 in the low pressure side, or through valve 8 to pipe 70 as in case 1.

3. Under the condition corresponding to case 1, arising when the system is in "reverse" operation, that is, when lack of cooling effect on the normally "low" pressure side of the system (now the discharge side) which like failure of condensing water in case 1 may result in abnormal pressures, the discharged vapors, not being able to pass through valve 7 because of the high pressure beyond, are automatically by-passed back to pipe 50 in the normally "high" pressure side, (now the suction side) through valve 6, or should pressure on both sides of the system become abnormal, are discharged to pipe 70 through valve 8 as in case 1.

4. "Reverse" operating conditions corresponding to case 2, that is those in which valves 63 in the discharge by-pass line 64 is not opened when the machine is reversed, a condition which may result disastrously in systems as they are usually constructed, give rise to no other action than that the vapors will be discharged through valve 7 operating automatically under the pressure to which it is adjusted instead of non-automatically as an ordinary hand operated by-pass valve at somewhat lower pressure, or be by-passed back to the discharge line 50 (now the suction line) through valve 6, or discharged through valve 8 in event of abnormal pressure there also, to pipe 70, as in case 1.

5. Similarly it can be shown that in event either the "high" or the "low" side of the system becomes the source of abnormally high pressure instead of pressure imposing element 1, as may occur in case of fire, valves 6 and 7 will first function to equalize such abnormally high pressure between pipes 50 and 67 in the "high" and the "low" sides of the system respectively, and then, should safe limits be exceeded, valve 8 will discharge the refrigerant through pipe 70 to the refrigerant conserver 16 and diaphragm discharging device 11 as in case 1.

6. Another serious source of danger lies in the possibility of closing all outlet valves on liquid receivers which may have become so completely filled with liquid as to afford no gas space into which, by the compression of the gas the liquid may expand under a subsequent rise in temperature. Such danger is avoided by the use of another similar,

though possibly very much smaller automatic relief valve 9, installed between the receiver 3 and some other part of the system, such as discharge line 50, connecting the pressure imposing means to the condenser. 70

7. In still other contingencies such as when brine coolers of the shell type are designed for operation under low pressure which may be exceeded if all outlet valves are closed, other similar automatic pressure relief valves such as 19 and 20 may be employed to advantage, in which case they would be connected to the brine coolers below stop valves 71 and 72 and so connected, since these coolers operate under low pressure, as to discharge into pipe 70 between valve 8 and the refrigerant discharge element 11. Such automatic pressure relief valves may, if desired, be set to discharge each at a different pressure as the strengths 85 of the containers and their working pressures may require.

Still another important application of my invention from the standpoint of refrigerant conservation, is the transferring back to the system, via the refrigerant conserver, of the refrigerant which leaks out through compressor piston rod stuffing boxes. This loss is considerable even in well operated plants and would be much greater were it not for the tightness with which such stuffing boxes have to be packed in order to withstand the high condensing pressure imposed by the compressors. Direct saving of ammonia leakage, through such stuffing boxes, 100 due to increased pressure on the packing is doubly disadvantageous, not only in that it results in direct loss of power, and the fuel required to produce it, but also in that the heat generated by the excessive friction 105 hastens the dissociation of the refrigerant. By applying an auxiliary stuffing box outside the customary one, and by connecting the chamber formed between the two, to pipe 70 beyond valve 8, the primary stuffing 110 box can be operated more loosely, the increased amount of refrigerant leaking therethrough being taken up and conserved in the refrigerant conserver and the fuel consumed in producing the excessive rod heating and the dissociation produced by such heating are largely eliminated. 115

Full protection against disruptive pressures will be realized in any part of the system thus equipped when its pressure relief 120 valve is set to discharge at any pressure above that of element 11. Full protection against loss of refrigerant will be realized when sufficient unsatisfied refrigerant absorbent capacity is provided in the refrigerant conserving element 16. The work of maintaining adequate refrigerant absorbing capacity in element 16 is facilitated by valves 73, and 74 on pipes 70 and 50, pressure gage 46 and the electrical signaling de- 125 130

vices 47. The gage indicates the exact pressure and the signaling device pressures above a predetermined point.

The means for conserving the ammonia that passes the valves either by leakage due to pressures below those for which they are set to discharge, or by actual discharge at these pressures, may vary widely with different systems of refrigeration and also with 10 the same system under different operating conditions.

In some cases the usual operating suction pressure of the pressure imposing means will be sufficiently low to allow of its 15 turn direct to the system through pipe 75 controlled by valve 76 and provided with a check valve 77 to prevent refrigerant flow in the opposite direction. Where suction pressures do not permit of this procedure the 20 refrigerant conserving device 16 is employed. It should have separate pipe connections to pipes 70 and 50 provided with stop valves 73 and 74, the former being open and the latter being closed while the conserving is taking 25 up the refrigerant, and the former being closed and the latter open when the refrigerant so taken up is being returned to the system.

The refrigerant conserving in the general 30 case is essentially a pressure resistant container filled with a substance capable of taking into solution or entering into chemical combination with the refrigerant under comparatively low pressures and normal cooling 35 water temperatures and from which the refrigerant may be again separated by the application of heat under sufficient pressure to allow of its return to, and liquefaction in, the condenser.

40 The medium employed in element 16 for taking up the refrigerant varies widely with different refrigerants and different systems. In machines of the ammonia absorption type for example the ammonia from several 45 safety valves may be absorbed in weak aqua-ammonia which, after thereby becoming strong aqua-ammonia, could either be pumped into the main generator of the system, or, where the amounts of ammonia 50 are small, it might be driven out of solution and into the condenser by the simple application of heat to the refrigerant conserving element.

In machines of the ammonia compression 55 type water or weak aqua-ammonia might be used as the absorbing element if the refrigerant is not to be returned to the refrigeration system but if the refrigerant is to be returned to the system, the use of 60 water or aqua-ammonia becomes prohibitively objectionable because of the inherent tendency of the water vapor to pass over to the condenser with that of the ammonia. Since it is imperative that the ammonia employed in refrigeration systems of the com-

pression and the reaction types, be as nearly anhydrous as possible, I replace the aqua-ammonia absorbent used in the absorption system, by a non-aqueous substance when used in connection with such system. The 70 media I employ in such systems do not take up ammonia by absorption, *per se*, but form with it ammoniates or so called addition products, by positive chemical reactions taking place between fixed proportions of the 75 substances in conformity to known chemical laws. A large number of substances exist capable of forming such addition products, among the most commonly known of which may be mentioned anhydrous-copper sulfate and a series of salts of alkaline earth metals. Since the reaction of formation of ammoniates with such substances takes place accompanied by evolution of heat, cooling means such for example as water jacket 42 80 shown in Fig. 1, or an internal cooling coil previously mentioned, should be provided when large quantities of ammonia are to be absorbed. Where the amount of ammonia is quite small however, as in the case of 90 only slight leakage through automatic safety or other types of valves, the heat generated by the reaction will usually be dissipated by direct radiation fast enough to prevent rise in temperature to the point 95 where it will prohibitively retard the reaction, and allow an accumulation of pressure above that for which the diaphragm device 11 is set to discharge.

When the compound employed in the 100 conserving has become inactive because of having united with practically its full complement of refrigerant, it is broken down into its original components by the application of heat. During this dissociation process valve 73 between the conserving and pipe 70 is closed and valve 74 between that element and the condenser is opened.

The refrigerant vapor driven into the condenser by this process is anhydrous and 110 accordingly gives rise to no operating complications in either compression or reaction machines. It is obvious that for convenience it may often be advisable to install two refrigerant conservers, one being held 115 in reserve for use while the alternate unit is absorbing and discharging refrigerant.

While the use of such a device would have, in a lesser degree, the disadvantage as regards leakage inherent to the pressure relief 120 valves now in use, it is obvious that the spirit of my invention also covers the employment of an automatic pressure relief valve, similar to those already described, or, since it will not be called upon to discharge against 125 pressure, a safety valve of the usual type in place of the diaphragm device 11. A safety valve when so used would be set to discharge at a pressure so much lower than that of the pressure relief valves 19 and 20 130

that with efficient operation of conserving device 16 the leakage therethrough would be slight because of the still lower pressure sustained by the refrigerant conserving means.

Briefly, the method of operation of the safety system I propose may be described as follows: In event of the rapid accumulation of excessive pressures in any part of the system the special automatic valve protecting that part will immediately relieve that part by passing a portion of the working fluid into a common discharge pipe closed by the diaphragm, which diaphragm, in event the refrigerant conserving means does not constantly operate to maintain a sufficiently reduced pressure between the valves and such diaphragm will be instantly swept away allowing an unrestricted discharge of the refrigerant to the atmosphere or other point of disposal.

To prevent loss of refrigerant under all pressures below that necessary to rupture the diaphragm, as well as a part of it while it is being discharged after the rupture of the diaphragm, since a back pressure of 10 pounds is allowable in the discharge pipe, the refrigerant conserving means above mentioned and hereinafter described in greater detail, is employed. The capacity of this conserving means should be sufficient to prevent the accumulation of sufficient pressure, due to valve leakage, to rupture the diaphragm. The diaphragm should fail only when the full force of the refrigerant is liberated by the opening of one or more of the special safety pressure relief valves, in case of excessive pressure, or that of the hand operated valves employed for discharging the refrigerant from the system in case of fire.

In the working out of the system all of the safety protection provided for in the present code of regulations for refrigeration plants has been provided for, as well as several possible conditions which might arise due to fire, and all without loss of refrigerant under normal operating conditions as long as the conserving means is kept in a constantly receptive condition. It is obvious that the loss due to the aggregate leakage of a large number of safety valves discharging into the atmosphere, as now employed, may become enormous, especially since such valves, once blown by pressure resulting either from regular operating conditions or those imposed for test purposes, seldom reseat tightly until they have been cleaned and not infrequently not until the seats have been reground, a requirement difficult and often impossible to satisfy under conditions of commercial operation. Under the serious conditions of ammonia shortage, obtaining in war times, the loss of that fluid through safety valves, and through dis-

charge under abnormal and leakage under normal conditions, makes the use of the present safety means demanded by municipal and State regulations for public safety, practically prohibitive.

I therefore provide in my invention, means for conducting away under low pressure, and for conserving, any part of the media that may pass slowly by leakage or otherwise, and I provide also for the escape, under a predetermined higher pressure, lower than the normal working of the system, of any media in excess of that which the conserving means is able to absorb either because of too rapid escape of the media, or failure of the conserving means to function, which may occur when an absorbent or a reacting medium is allowed to take up its full complement of refrigerant.

It will therefore be seen that the present invention is designed to accomplish in a reliable and efficient manner all of the objects and advantages herein set forth.

I claim:

1. In a fluid pressure apparatus, in combination, a normally fluid-tight chamber, automatic high pressure relief means for passing fluid into said fluid-tight chamber, means connected with said chamber and responsive to a relatively materially lower pressure for permitting discharge of the fluid from said chamber, and conserving means including a medium capable of absorbing the fluid at pressures below that necessary to actuate the fluid discharging means.

2. In a fluid pressure apparatus, in combination, a normally fluid tight chamber, automatic high pressure relief means for passing fluid into said fluid-tight chamber, means connected with said chamber for conserving the fluid so passed on the occurrence of high pressure and by leakage through said relief means under lower pressure, and normally fluid tight means responsive to a pressure lower than that required to actuate the high pressure relief means for permitting discharge of the fluid from the normally fluid tight chamber.

3. In a fluid pressure apparatus, in combination, a normally fluid tight chamber, automatic high pressure relief means for passing fluid into said normally fluid tight chamber, means connected with said chamber for conserving the fluid so passed on the occurrence of high pressure and by leakage through said relief means under low pressure, and a normally fluid tight barrier, rupturable by a pressure materially lower than that required to actuate the pressure relief means for permitting discharge of the fluid from the normally fluid tight chamber.

4. In a fluid pressure apparatus, in combination, a normally fluid tight chamber, automatic high pressure relief means for pass-

ing fluid into said normally fluid tight chamber, means associated with said chamber for conserving the fluid so passed on the occurrence of high pressure and by leakage 5 through said relief means under lower pressure, and means including a normally fluid tight diaphragm rupturable by pressure materially lower than that required to actuate the high pressure relief means, for permitting discharge of the fluid from the normally fluid tight chamber.

5. In a fluid pressure apparatus, in combination, a pressure responsive means for liberating a part of the fluid from such apparatus, 15 for the relief of and on the occurrence of excessive pressure in said apparatus, means for conserving the liberated fluid, means for returning the conserved fluid to circulation in the apparatus, and pressure 20 responsive means for discharging from the apparatus fluid in excess of that which can be so conserved and returned.

6. In a fluid pressure apparatus, in combination, a pressure imposing means, a pressure 25 resistant fluid conduit, means responsive to a predetermined pressure for passing high pressure fluid from the discharge side to the suction side of the pressure imposing means, means responsive to a predetermined 30 pressure higher than that of the primary pressure responsive means for relieving any excessive pressure in the pressure resistant fluid conduit obtaining after the operation of the primary means, means for conserving 35 the fluid discharged, and means for discharging such fluid as is not conserved on the occurrence of a predetermined pressure materially lower than that required to actuate the auxiliary fluid discharging means.

40 7. In a refrigeration apparatus, in combination, a normally fluid tight chamber, automatic high pressure relief means for passing refrigerant into said normally fluid tight chamber, means associated therewith responsive to materially lower pressure for permitting 45 the discharge of the refrigerant from such chamber, and conserving means including a medium capable of combining with the refrigerant under pressures below that necessary to actuate the refrigerant discharging means.

8. In a refrigerating apparatus, in combination, a normally refrigerant tight chamber, automatic high pressure relief means 55 for passing the refrigerant into said normally refrigerant tight chamber, means associated with said chamber for conserving the refrigerant so passed on the occurrence of high pressure or by leakage through said 60 relief means under lower pressure, and normally refrigerant tight means responsive to pressure materially lower than that required to actuate the high pressure relief means, for permitting discharge of the refrigerant from 65 the normally refrigerant tight chamber.

9. In a refrigeration apparatus, in combination, a normally refrigerant tight chamber, automatic pressure relief means for passing refrigerant into said normally refrigerant tight chamber, means associated 70 with said chamber for conserving the refrigerant so passed on the occurrence of a high pressure or by leakage through said relief means under lower pressure, and a normally refrigerant tight barrier rupturable by a pressure materially lower than that required to actuate the pressure relief means, for discharging the refrigerant from the normally refrigerant tight chamber.

10. In a refrigeration apparatus, in combination, a normally refrigerant tight chamber, automatic high pressure relief means for passing the refrigerant into said normally refrigerant tight chamber, means associated with said chamber for conserving 85 the refrigerant so passed on the occurrence of high pressure or by leakage through said relief means under lower pressure, and a normally refrigerant tight diaphragm, rupturable by a pressure materially lower than 90 that required to operate the high pressure relief means, for discharging the refrigerant from the normally refrigerant tight chamber.

11. In a refrigeration apparatus, in combination, a continuous pressure resistant refrigerant conduit including a refrigerant compressor, an auxiliary conduit, automatic means responsive to and for the purpose of relieving predetermined excessive pressure 100 within said first-mentioned conduit for discharging refrigerant to said auxiliary conduit, means responsive to a substantially lower pressure for discharging refrigerant from said auxiliary conduit, and means connected thereto for normally drawing away the refrigerant and thereby maintaining therein pressure lower than that required to actuate the auxiliary conduit pressure discharging means.

12. In a refrigeration apparatus, in combination, a continuous pressure resistance refrigerant conduit including a refrigerant compressor, an auxiliary conduit, automatic means responsive to and for the purpose of relieving predetermined excessive pressure 115 within said first-mentioned conduit for discharging refrigerant to said auxiliary conduit, means responsive to a substantially lower pressure for discharging refrigerant 120 from such auxiliary conduit, and means including a medium capable of combining with the refrigerant, connected to said auxiliary conduit for normally drawing away the refrigerant and thereby maintaining in said 125 auxiliary conduit pressures lower than that required to actuate the auxiliary conduit pressure discharging means.

13. In a refrigeration apparatus, in combination, a continuous pressure resistant re- 130

frigerant conduit including a refrigerant compressor, an auxiliary conduit, automatic means responsive to and for the purpose of relieving predetermined excessive pressure 5 within, said first-mentioned conduit for discharging refrigerant to said auxiliary conduit, means responsive to a substantially lower pressure for discharging the refrigerant from said auxiliary conduit, and means, 10 including a compound capable of reacting chemically with the refrigerant connected to said auxiliary conduit for normally drawing away the refrigerant and thereby maintaining therein pressures lower than that required to actuate the auxiliary conduit pressure 15 discharging means.

14. In a refrigeration apparatus, in combination, a continuous pressure resistant refrigerant conduit including a refrigerant 20 compressor, an auxiliary conduit, automatic means responsive to and for the purpose of relieving predetermined excessive pressure within said first-mentioned conduit for discharging refrigerant to said auxiliary conduit, means responsive to a substantially lower pressure for discharging refrigerant from said auxiliary conduit, means connected to said auxiliary conduit for indicating a condition of impending operation of 25 the refrigerant discharging means, and means for normally drawing away the refrigerant and thereby maintaining within the auxiliary conduit pressures lower than that required to actuate the auxiliary conduit pressure discharging means.

15. In a refrigeration apparatus, in combination, a continuous ammonia pressure resistant conduit including a pressure imposing means, an auxiliary conduit, automatic 40 means responsive to and for the purpose of relieving predetermined excessive ammonia pressure within said first-mentioned conduit for discharging ammonia to said auxiliary conduit, means responsive to a substantially lower pressure for discharging ammonia from such auxiliary conduit, and means connected to said auxiliary conduit for normally drawing away the refrigerant and thereby maintaining in said auxiliary conduit pressures lower than that required to actuate the auxiliary conduit pressure discharging means.

16. In a refrigeration apparatus, in combination, a continuous ammonia pressure resistant conduit including a pressure imposing means, an auxiliary conduit, automatic 55 means responsive to and for the purpose of relieving predetermined excessive pressure

within said first-mentioned conduit for discharging ammonia to said auxiliary conduit, 60 means responsive to a substantially lower pressure for discharging ammonia from such auxiliary conduit, and means including a compound capable of reacting chemically with the ammonia to form ammoniates connected to said auxiliary conduit for normally drawing away the ammonia and thereby maintaining in said auxiliary conduit pressures lower than that required to actuate the auxiliary conduit pressure discharging means. 65

17. In a refrigeration apparatus, in combination, a continuous ammonia pressure resistant conduit including a pressure imposing means, an auxiliary conduit, automatic 70 means responsive to and for the purpose of relieving predetermined excessive pressure within said first-mentioned conduit, means responsive to a substantially lower pressure for discharging ammonia from said auxiliary conduit, means including a compound capable of reacting chemically with the ammonia to form ammoniates connected to said auxiliary conduit for normally drawing away the ammonia and thereby maintaining 75 in said auxiliary conduit pressures lower than that required to actuate the auxiliary conduit pressure discharging means, means for cooling said ammoniate-forming means and thereby facilitating the formation of 80 such ammoniates, means for heating said ammoniate-forming means and thereby dissociating such ammoniates, and means for returning the ammonia product of such dissociation to the ammonia conduit. 85

18. In a refrigeration apparatus, in combination, a continuous pressure resistant refrigerant conduit including a refrigerant compressor, an auxiliary conduit, automatic 90 means responsive to and for the purpose of relieving predetermined excessive pressure within said first-mentioned conduit for discharging refrigerant to said auxiliary conduit, means responsive to a substantially lower pressure for discharging refrigerant 95 from said auxiliary conduit, and means connected to said auxiliary conduit for normally maintaining therein pressures lower than that required to actuate the auxiliary conduit pressure discharging means. 100

In testimony whereof I affix my signature in the presence of two witnesses.

FRED E. MATTHEWS.
